GRAPHIC RECORDER

Roy L. Van Winkle, Edmond, and William L. Lankford, Jr., and Carl S. Ward, Oklahoma City, Okla., assignors to The Geograph Company, Oklahoma City, Okla., a corporation of Oklahoma

Filed Jan. 4, 1963, Ser. No. 73,048

Term of patent 14 years

(Cl. D26—14)

The figure is a perspective view of our new design of a graphic recorder in open position.

The semi-cylindrical cover is hinged to the plain back in the same relation as the front opening and closes flush with the front end wall. The undisclosed end is like the end shown.

We claim:

The ornamental design for a graphic recorder, substantially as shown and described.
